UNITED STATES PATENT OFFICE.

FRANCES R. VAN HOUTEN, OF DETROIT, MICHIGAN.

TIE STRAIGHTENER.

Application filed October 30, 1925. Serial No. 65,837.

This invention relates to a device designed for stretching neckties to remove wrinkles which are prevalent in a tie after it has been worn.

5 An important object of the invention is to provide a necktie stretcher formed of a single length of resilient metal, the same being constructed in such a way that an outward pressure will be directed to the side edges 10 of the tie to stretch the same.

A still further object of the invention is to provide a device of this character which may be employed for stretching wide or narrow ties.

15 With the foregoing and other objects in view which will appear as the description proceeds, the invention resides in the combination and arrangement of parts and in the details of construction hereinafter described 20 and claimed, it being understood that changes in the precise embodiment of the invention herein disclosed, may be made within the scope of what is claimed, without departing from the spirit of the invention.

25 Referring to the drawing:

Figure 1 is a perspective view illustrating a stretching device constructed in accordance with the invention as positioned in a 30 tie.

Figure 2 is a perspective view of the stretching device.

Referring to the drawing in detail, the stretcher includes a length of substantially flat metal bent intermediate its ends as indicated at 5 to provide the leg members 6 and 7 respectively.

The leg members 6 and 7 lie in close en-

gagement with each other at a point adjacent to the portion 5 so that the device will 40 present a relatively flat surface to insure against wrinkles being formed by the stretcher, at this point.

From the foregoing it will be seen that the leg members 6 and 7 will normally lie in a 45 position as shown by Figure 2, to the end that when the device is inserted within the open end of a necktie, the outer edges of the leg members 6 and 7 will be forced into engagement with the inner surfaces of the 50 edges of the necktie and exert a lateral pressure thereon.

With the stretching device in this position, it is contemplated to hold the device over a 55 steam jet to cause the cloth of which the necktie is constructed to become dampened. The necktie is now permitted to dry while the stretcher is in position, to the end that all wrinkles will be removed and the tie restored to its normal condition before it has 60 been worn.

I claim:

A tie stretcher embodying a length of flat metal bent intermediate its ends, to provide 65 leg members, the adjacent faces of the leg members contacting with each other throughout portions of their lengths, the free ends of the leg members being arranged in spaced relation with each other, and the inner adjacent faces of the leg members lying in the 70 same plane.

In testimony that I claim the foregoing as my own, I have hereto affixed my signature.

FRANCES R. VAN HOUTEN.
